ADJUSTABLE TABLE LAMP OR SIMILAR ARTICLE

Samuel J. Koch, 26 Martin Court, Great Neck, N.Y.

Filed June 28, 1962, Ser. No. 70,725

Term of patent 3½ years

(Cl. D48—20)

FIG. 1

FIG. 2

FIG. 2

FIG. 3

FIG. 4

FIG. 1 is a perspective view of an adjustable table lamp or similar article showing my new design in its open and extended position;

FIG. 2 is a perspective view thereof in its collapsed position;

FIG. 3 is a side elevation thereof as shown in FIG. 2;
FIG. 4 is a top plan view thereof as shown in FIG. 2.
The bottom of the base member illustrated in FIG. 1 is flat and plain and the underside of the shade is open and conventional.

I claim:

The ornamental design for an adjustable table lamp or similar article, substantially as shown and described.
